UNITED STATES PATENT OFFICE.

GEORGE B. McCORMACK, OF JERSEY CITY, NEW JERSEY.

PAPER-FEEDER.

1,240,464.

Specification of Letters Patent. Patented Sept. 18, 1917.

Application filed October 31, 1916. Serial No. 128,698.

To all whom it may concern:

Be it known that I, GEORGE B. McCORMACK, a citizen of the United States, residing at Jersey City, in the county of Hudson and State of New Jersey, have invented new and useful Improvements in Paper-Feeders, of which the following is a specification.

This invention relates to a paper feeder. 10 One of the objects of the present invention is to provide a simple, easily operated automatic paper feeder which is adapted to be attached to practically any standard form of printing press or like machine now 15 in use.

Another object of the invention is to provide means for blowing hot air through the sheets to dry and separate same and also to expel any static electricity which often 20 exists under certain weather conditions.

Further objects will hereinafter appear. The invention consists of the parts and the construction and combination of parts as hereinafter more fully described and 25 claimed, having reference to the accompanying drawings in which:—

Figure 1 is a side elevation of the paper feeder.

Fig. 2 is a plan view of same.
30 Fig. 3 is a front end view.

Referring to the drawings in detail, A indicates in general a main frame consisting of four T shaped connected standards 2 and 3, between which is supported a cylinder 4. Mounted in the cylinder is a plunger 5 on the upper end of which is secured a table 6 which is adapted to receive and support a stack of paper such as indicated at 7. Secured to the lower side of the table 40 is a pair of brackets 8 and 9 which are slotted at their outer ends to straddle the T shaped standards 2 and 3, in this manner forming a vertical guide for the table and the plunger which enters the cylinder 4. The lower end of the cylinder is extended as at 10 to receive a heating coil 11, and a gas burner 12, the function of which 45 will hereinafter be described. Journaled in brackets 12 and 13 formed on one side of the main frame, is a driving shaft 14 to which power is transmitted by means of a belt and pulley 15. Journaled at right angles to said shaft in bearings 16 is an intermediate shaft 17 to which power is transmitted from the driving shaft 14 by

means of gears 18. Secured on the forward end of the shaft 14 is a disk 19 on the outer face of which projects a crank pin 20. Journaled in the frame below the table 6 centrally of the standards 2 and 3, 60 is a shaft 21 on the outer end of which is secured a disk 22 which is also provided with a crank pin 23, the crank pins 20 and 23 being connected by means of a link or connecting rod 24 to permit power to be 65 transmitted from the shaft 14 and to permit the two shafts to be driven in unison. Secured on the shaft 21 is a pair of cams 25 which are adapted to engage with rollers 26 secured on the lower side of the table 70 6. Each cam is offset as indicated at 27 to permit the cams to slowly raise the table and plunger with relation to the cylinder 4 and also to permit the plunger and table to drop with considerable speed when the 75 offset portions of the cams are reached. The lower end of the cylinder is connected with the heating coil 11 and this is in turn connected with a flexible tube 28 which in turn connects with a nozzle 29 secured on 80 the table adjacent the forward end of the paper stack 7.

Mounted on the discharging end of the heating coil is a check valve 30, and mounted in the lower end of the plunger is a check 85 valve 31. The slow upward movement of the plunger and table transmitted through the cams 25 causes the upper check valve 31 to open to permit the cylinder to charge with air. This valve however closes when 90 the plunger and table is permitted to settle, and thus causes the air to be discharged through the heating coil, the check valve 30, the flexible tube 28, and the nozzle 29, directly against the end of the paper stack 7. 95 The drop of the plunger and table being limited or cushioned entirely by the escaping air from the cylinder while the up movement is limited by the piston engaging the cylinder top. The air in its passage through 100 the coil 11 is heated to any desirable degree by regulating the flame of the burner 12 and as this air is intermittently forced endwise into the paper stack 7, it can readily be seen that the individual sheets will be thoroughly 105 dried, separated and heated to such an extent that static electricity is practically eliminated. Paper unless heated, is often troublesome, and the individual sheets often have a tendency to adhere, due to the static 110

electricity which is prevalent during certain atmospheric conditions. This condition is entirely overcome by the present heating arrangement. Pivotally mounted upon a shaft 5 33 journaled in the upper ends of the bracket arms 13, is a frame 34 in the outer end of which is journaled a pair of composition rollers 35 and a pair of cleaning rollers 36. The shaft 33 is continuously driven from the 10 intermediate shaft 17 by means of a sprocket chain drive 37, and the composition rollers 35 are similarly driven from shaft 33 by a sprocket chain drive 38. Mounted forward of the composition rollers 35, is a pair of 15 intermediate stripping rollers 39 which are driven in unison with the composition rollers by means of the sprocket chain drive 40, and journaled in the outer lower end of the frame 34 is a roller 41, which carries a conveyor belt 42.

This conveyor belt passes over a similar roller secured upon the shaft 33, and is provided for the purpose of carrying away the individual sheets delivered thereto by means 25 of the composition rollers 35 and the intermediate stripping rollers 39. The individual sheets carried up by the conveyor belt 42 are discharged from the roller on the shaft 33, being received by a secondary conveyor 30 43 or any other suitable mechanism. The frame 34 as previously described, is pivotally mounted on the shaft 33, and as considerable weight is imposed thereon by the different rollers and chains, it can readily 35 be seen that it becomes necessary to counter-weigh the frame to prevent the composition rollers 35 from exerting too much pressure upon the paper stack.

A pair of extension arms 44 provided with 40 adjustable counter-weights 45 have therefore been employed. These weights permit an equal distribution of the weight imposed upon the frame 34, in fact such a nicety of balance may be secured that any pressure 45 desired may be imposed on the composition rollers 35 when these engage the topmost sheet of the stack 7.

The pivotal movement of the frame 34 is limited in a downward direction by a 50 bracket 50 and a stop pin 51, while the upward movement is entirely unrestricted. The operation of the feeder as a whole will be as follows:—

Power transmitted to shaft 14 through 55 the belt 15 is in turn transmitted to the intermediate shaft 17 and shaft 33 through the beveled gears 18 and the sprocket chain drive 37. Power is simultaneously transmitted to the shaft 21 through the crank pins 20 and 23, and the connecting link 24. Reciprocal movement is in this manner transmitted to the plunger 5 and the table 6 once during each revolution on the shafts 14 and 21, in other words it can be seen that the table 6 supporting the paper stack 7

is raised up into engagement with the composition rollers 35 once during each revolution, and is again permitted to settle to expel the air admitted to the cylinder 4 to permit this to be discharged through the nozzle 29 into the stack as previously described. The raising of the paper stack into engagement with the composition roller 35 which is continuously revolved, causes this to remove the uppermost sheet by frictional pull in the direction of arrow a. The stripping rollers 39 interposed between the composition rollers, prevent the sheet from being wrapped around same and therefore delivers each individual sheet to the conveyor 80 42, which in turn conveys it to the secondary conveyor 43 from where it may be delivered to a printing press or any other machine or device desired.

The rollers 60 which are mounted above the conveyor 42, are merely provided for the purpose of preventing the individual sheets from flying off the conveyor where the sheets are delivered at considerable speed. The upward movement of the table is limited 90 entirely by the lift of the cams 25. It is therefore always uniform and will consequently raise the frame 34 about the pivotal mounting 33 a variable distance depending entirely upon the paper stack 7. The timing is however such that only one sheet can be removed during each engagement. The lowering of the stack when the cams 25 pass out of engagement with the rollers 26, permits the stack 7, together with the table and plunger, to drop with considerable speed. The frame 34 in this manner follows until its downward movement is limited by the pin 51 and the stop bracket 50 while the continued downward movement of the parts 105 mentioned causes the air previously admitted to the cylinder 4 to be expelled through the heating coil and the nozzle 29. The upward movement of the table is always such that a whole stack of paper may be 110 fed from top to bottom without necessitating any adjustment or care on the part of the attendant. The swinging movement of the frame 34 being of course greater when the paper stack is high and comparatively 115 smaller as the stack decreases.

The cleaning rollers 36 may be constructed of felt, or any other suitable material, and are only employed for the purpose of removing any paper lint, or like material, 120 which might have a tendency to adhere to the face of the composition rollers 35 while these are feeding. The composition rollers are in this manner automatically cleaned without further attention or care.

The feeder as a whole is entirely automatic, and is so simple in construction that comparatively little care or skill as far as the operation is concerned, is required.

The materials and finish of the several 130

parts of the feeder may otherwise be such as the experience and judgment of the manufacturer may dictate.

I wish it understood that various changes 5 in form, proportions and minor details of construction may be resorted to within the scope of the appended claims, and that I do not wish to limit myself to the specific design or construction here shown.

10 Having thus described my invention, what I claim and desire to secure by Letters Patent is:—

1. An automatic paper feeder comprising a table adapted to support a stack of paper, 15 a revolving vertically movable roller mounted above the stack, and means for successively raising and lowering the table upon feed of each sheet to bring the topmost sheet of the stack into engagement with the roller 20 to raise the latter.

2. An automatic paper feeder comprising a table adapted to support a stack of paper, a pivotally mounted frame, a revolving roller journaled in the free end of the frame 25 above the paper stack to partake of the frame movements, and means for raising and lowering the table to bring the topmost sheet of the stack into and out of engagement with the roller.

30 3. An automatic paper feeder comprising a table adapted to support a stack of paper, a pivotally mounted frame, a plurality of revolving feed rollers journaled in the free end of the frame, a plurality of revolving 35 stripping rollers journaled in the frame adjacent the feeder rollers and intermediate of same, and means for raising and lowering the table to bring the topmost sheet in the stack into engagement with the feeding rollers.

40 4. An automatic paper feeder comprising a table adapted to support a stack of paper, a pivotally mounted frame, a plurality of revolving feed rollers journaled in the free 45 end of the frame, a plurality of revolving stripping rollers journaled in the frame adjacent the feeder rollers and intermediate of same, means for raising and lowering the table to bring the topmost sheet in the 50 stack into engagement with the feeding rollers, and a conveyer belt carried by the pivotally mounted frame, operating in unison with feeding and stripping rollers to discharge each sheet as it is removed from the stack by the feeding rollers.

55 5. An automatic paper feeder comprising a table adapted to support a stack of paper, a pivotally mounted frame, a revolving roller journaled in the free end of the flange 60 above the paper stack, and means for raising and lowering the table to bring the topmost sheet of the stack into engagement with the roller, means for limiting the downward swinging movement of the free end 65 of the pivotally mounted frame, and means

for limiting both the upward and downward movement of the table.

6. An automatic paper feeder comprising a table adapted to support a stack of paper, a pivotally mounted frame, a plurality of 70 revolving feed rollers journaled in the free end of the frame, a plurality of revolving stripping rollers journaled in the frame, adjacent the feeder rollers and intermediate of same, and means for raising and lowering the table to bring the topmost sheet in the stack into engagement with the feeding rollers, means for limiting the downward swinging movement of the free end of the pivotally mounted frame, and means for 75 limiting both the upward and downward movement of the table.

7. An automatic paper feeder comprising a table adapted to support a stack of paper, a pivotally mounted frame, a plurality of revolving feed rollers journaled in the free end of the frame, a plurality of revolving stripping rollers journaled in the frame adjacent the feeder rollers and intermediate of same, means for raising and 80 lowering the table to bring the topmost sheet in the stack into engagement with the feeding rollers, a conveyer belt carried by the pivotally mounted frame, operating in unison with feeding and stripping rollers 85 to discharge each sheet as it is removed from the stack by the feeding rollers, means for limiting the downward swinging movement of the free end of the pivotally mounted frame, and means for limiting both the upward and downward movement of the 90 table.

8. An automatic paper feeder comprising a table adapted to support a stack of paper, a revolving roller mounted above the stack, means for raising and lowering the table to bring the topmost sheet of the stack into engagement with the roller, a nozzle mounted adjacent one end of the paper stack, and means operated by the 100 table movements for intermittently forcing hot air through the nozzle against the end of the stack.

9. An automatic paper feeder comprising a table adapted to support a stack of paper, a pivotally mounted frame, a revolving roller journaled in the free end of the flange above the paper stack, means for raising and lowering the table to bring the topmost sheet of the stack into engagement 115 with the roller, means for limiting the downward swinging movement of the free end of the pivotally mounted frame, means for limiting both the upward and downward movement of the table, a nozzle 120 mounted adjacent one end of the paper stack, and means for intermittently forcing hot air through the nozzle against the end of the stack.

10. An automatic paper feeder compris- 130

ing a frame, a feeding roller, a table reciprocally mounted in the frame adapted to raise a stack of paper into and out of engagement with the feeding roller, a cylinder mounted below the table, a plunger secured to the table extending into the cylinder valves connected with the cylinder adapted to admit and expel air when the table and plunger reciprocates, a nozzle mounted adjacent the table, and a connection formed between said nozzle and the cylinder adapted to convey the expelled air from the cylinder to the nozzle.

11. An automatic paper feeder comprising a frame, a feeding roller, a table reciprocally mounted in the frame adapted to raise a stack of paper into and out of engagement with the feeding roller, a cylinder mounted below the table, a plunger secured to the table extending into the cylinder valves connected with the cylinder adapted to admit and expel air when the table and plunger reciprocates, a nozzle mounted adjacent the table, a connection formed between said nozzle and the cylinder adapted to convey the expelled air from the cylinder to the nozzle, and means for heating the air before it discharges through the nozzle.

12. In an automatic paper feeder, feeding means, means for supporting a stack of sheets, means for reciprocating the supporting means, and means for directing a heated air blast against the edges of the stack only during the idling movement of the supporting means.

13. In combination with sheet feeding means, means for supporting a stack of sheets, means to move the supporting means into sheet feeding position, and means actuated by the supporting means to direct an air blast against the stack.

14. In combination with sheet feeding means, means for supporting a stack of sheets, means to reciprocate the supporting means to cause same to move into and out of sheet feeding position, and means actuated by the idling stroke of the supporting means to direct an air blast against the stack.

15. In combination with sheet feeding means, and a sheet receiving table, an air compression cylinder having a piston therein, means to reciprocate the table, means connecting the piston and table whereby upon idling movement of the table the piston will be given a working stroke, and

means to conduct the compressed air to sheets placed on the table.

16. In combination with sheet feeding means and a reciprocatory table, means to direct air against an edge of the stack on the table, means to heat the air, and means to force the heated air through said directing means upon the idle stroke of the table.

17. In combination with sheet feeding means and a table, means engageable with the table to raise same and disengageable therefrom to permit the table to drop, air compression means operable by the dropping movement of the table, and means to direct the compressed air to the sheets on the table.

18. In combination with sheet feeding means, a table, an air compressor, a heating coil connected to the air compressor discharge, means to heat the coil, and means to discharge the air from the coil onto the stack on the table.

19. In combination with sheet receiving means, swingable sheet feeding means, means to intermittently operate the sheet receiving means to bring same successively into and out of engagement with the feeding means upon each sheet feeding operation, and means associated with and partaking of the swinging movements of the sheet feeding means for conveying the fed sheets away from the feeding means.

20. In combination with a sheet receiving table, a swingable frame, sheet feeding means on the frame, a conveyer on the frame, means to balance the frame, and means to successively move the table into and out of engagement with the sheet feeding means upon each sheet feeding operation.

21. In combination with a sheet receiving table, swinging sheet feeding means engageable with the stack on the table, means to restrict the extent of downward movement of the feeding means, and means to move the table into and out of sheet feeding position so as to swing and thereby alternately raise and lower said sheet feeding means by contact of the table with said sheet feeding means.

In testimony whereof I have hereunto set my hand in the presence of two subscribing witnesses.

GEORGE B. McCORMACK.
